LOAD-HANDLING SLING

George E. Moore, Muskegon, Mich., assignor to
 Manning, Maxwell & Moore, Inc., Muskegon,
 Mich., a corporation of New Jersey

Application February 17, 1949, Serial No. 76,914

1 Claim. (Cl. 294—74)

1

The invention relates to load-handling slings and more particularly to slings of the type used in connection with hoists for supporting bulky or heavy objects to be lifted.

The primary object of the invention is to provide an improved sling of the above general character in which angular adjustment of the load may be effected while the load is suspended.

A more specific object is to provide a load-handling sling in which the relative lengths of the respective legs may be adjusted easily and safely while under load and in which the adjustments are effectively maintained at all times.

Other objects and advantages of the invention will become apparent from the following detailed description of the preferred embodiment illustrated in the accompanying drawing, in which:

Figure 1 is a side view of a load-handling sling embodying the features of the invention.

Fig. 2 is a sectional view taken in a vertical plane substantially on the line 2—2 of Fig. 1.

Fig. 3 is a sectional view taken in a vertical plane substantially on the line 3—3 of Fig. 2.

Fig. 4 is a perspective view of the load sheave of the sling.

While the invention is susceptible of various modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claim.

The improved sling comprises generally a load block 8 adapted to be suspended from a hoist or the like and having a pair of legs or load-supporting elements 9 and 10 depending at opposite sides. The load-supporting elements 9 and 10 are provided at their lower or free ends with suitable attaching devices, such as hooks 11 for attachment to an object to be lifted. At their upper ends the elements 9 and 10 are anchored at opposite sides of and in laterally spaced relation to the rotational axis of a supporting member 12 journaled on the block 8. Accordingly, by rotating the supporting member the effective lengths the respective elements may be varied to adjust the angular position of the load supported thereby. Suitable drive means, preferably of the self-locking type, is provided for rotating the supporting member 12 manually and for preventing its rotation under the influence of the supported load.

2

While the load block 8 may be fabricated from parts welded or otherwise secured together, the preferred form shown in Figs. 2 and 3 comprises a casting having spaced parallel side members 13 connected at opposite sides by integral front and rear cross members 14. The supporting member 12 is carried between the side members 13 and serves to transmit the load from the elements 9 and 10 to the block. At their upper ends the side members 13 are joined by an integral cross member 16 shaped for engagement with the hook or other connecting device provided on the hoist. Preferably the side members are of generally oval configuration to present a pleasing, streamlined appearance and their upper ends are somewhat tapered to afford convenient access to the member 16 for attachment to the hoist hook.

In the exemplary sling, the load-supporting elements 9 and 10 constitute the end portions of a unitary flexible member 20, herein shown as a conventional short link chain. To provide for the anchoring of the elements, the supporting member 12 is constructed in the form of a sprocket wheel or sheave having peripherally opening pockets 21 spaced apart circumferentially thereof to receive alternate horizontal chain links. The pockets 21 are separated by tooth-like projections 22 spaced apart axially of the sprocket to define channels for the reception of the vertical chain links. With this construction slippage of the chain relative to the sprocket wheel is effectually prevented.

Rotatable support for the sprocket wheel 12 is provided by a shaft 23 supported between the side members 13 of the load block and equipped with a conventional sleeve bushing 24. As indicated above, drive means is provided for rotating the supporting member 12 manually to adjust the legs or load-supporting elements 9 and 10 of the sling. The drive means preferably comprises a self-locking mechanism operative to prevent rotation of the member under the influence of the load imposed on the load-supporting elements thus serving to automatically maintain the adjustment. As herein shown, the drive means comprises a worm 25 (Figs. 1 and 2) fixed on a shaft 26 journaled in the cross members 14 and suitably anchored against axial movement. The worm 25 is positioned to coact with a worm wheel 27 rigid with the member 12, the worm wheel in this instance, being formed integral with and at one end of the member. The shaft 26 is extended at one side of the load block 8 and is squared as at 28 for the reception

of a wrench or hand crank whereby it may be conveniently rotated.

Due to the side-by-side arrangement of the supporting member 12 and worm wheel 27, the load applied to the block 8 through the elements 9 and 10 will be slightly off center. In order to prevent tilting of the block, provision is made for locating the connection with the hoist line directly above the elements. In the present instance this is accomplished by forming the cross member 16 with a circumferential hook-locating groove 29 appropriately located with respect to the chain-receiving pockets of the supporting member.

In the operation of the improved sling, the legs or elements 9 and 10 are attached to the load at laterally spaced points by means of the hooks 11. These hooks may engage directly with suitable portions of the load or conventional connecting devices such as load rings 30 may be employed. When the load is to be suspended in a horizontal position the elements 9 and 10 of the sling are adjusted to equal lengths, as shown in Fig. 1. Alternatively, either element may be lengthened and the other shortened correspondingly if the load is to be tilted at an angle or if the points of connection with the sling are disposed in different horizontal planes.

Such adjustments may be readily effected after a load has been lifted by simply turning the worm shaft 26 in the proper direction. This serves to turn the supporting member 12 to which the elements are anchored, thereby appropriately varying the effective lengths of the elements. By reason of this adjustability while under load, the sling is particularly well adapted for use in installing or removing engines in automotive, marine or other motorized equipment. For this purpose it may be attached to the engine while adjusted to the position shown in Fig. 1, and after an initial lift it may be adjusted to change the angle of the load as required. This is advantageous when the engine has a transmission attached thereto or has other projecting parts requiring tilting to clear obstructions. The adjustments, of course, are effectively maintained due to the locking action of the worm and worm wheel.

I claim as my invention:

A load-handling sling comprising, in combination, a load block having a one-piece frame consisting of a single open casting, said frame including two flat upright side members having a generally elliptical configuration larger at the lower end than at the upper end, said side mem-

bers being spaced apart from each other and interconnected at their upper ends by a generally cylindrical top cross member forming an integral part of said side members and shaped for co-operation with a support member, an axle shaft extending between the central sections of the broad lower portions of said side members and located upwardly a substantial distance from the lower ends of said members, a generally round load supporting element rotatably mounted on said axle shaft, a load carrying chain disposed over said element and having opposite ends extending downwardly from opposite sides thereof, said element including an annular sheave having indentations thereon for receiving links of said chain in non-slip relation and an annular worm wheel integrally formed with said sheave and spaced from said indentations along said axle shaft, the diametrical dimensions of said rotatable element being commensurate with but slightly less than the width of said side members so that said side members cover opposite ends of said element in protective relation thereto, two opposed side cross members disposed generally parallel to said top cross member and connecting opposed front and rear portions of the vertical side edges of said side members, said side cross members being integrally formed with said side members and located substantially on a level with the upper extension of said worm wheel, a shaft journaled in said side cross members to extend across said worm wheel, and a worm on said shaft meshing with said worm wheel.

GEORGE E. MOORE.
